UNITED STATES PATENT OFFICE

HOMER H. VANDIVORT, OF BADO, MISSOURI, ASSIGNOR OF ONE-FOURTH TO LUTHER L. GRISHAM, ONE-FOURTH TO RICHARD B. GRISHAM, AND ONE-FOURTH TO RAYMOND C. MILES, ALL OF ELK CREEK, MISSOURI

COLLAPSIBLE BOX-CARRYING MEANS

Application filed May 12, 1928. Serial No. 277,250.

The present invention pertains to improvements in means for securing collapsible boxes, and involves means whereby a box of the collapsible nature may be filled and then secured by the novel fastening means hereinafter fully described.

The prime object of this invention resides in the provision of fastening means for collapsible boxes, wherein the collapsible box may be reused numerous times, thus permitting an enormous saving in the cost of shipping commodities and the like.

Another object resides in the provision of such means as above set out, wherein the same may be folded and returned with the collapsed box to the consignor, the same requiring but very small space when in this collapsed condition.

Other objects and advantages of this invention will become apparent as the same is better understood from the following specification and claims.

In the drawings:—

Figure 1 represents a perspective view of a collapsible box equipped with the present novel fastening means.

Figure 2 represents an end view of the collapsible box with the fastening means thereto.

Figure 3 represents a fragmentary portion 30 of one corner of a collapsible box with the fastening means secured thereon.

Figure 4 represents one end of the fastening strap, and

Figure 5 represents the novel driven element employed for securing the strap in place on the box.

Now for a more detailed description of this invention, reference is made to the drawing wherein like numerals designate like parts.

The fastening means to be disclosed in the following specification, may be employed with numerous types and styles of box constructions, but for the purpose of disclosing the manner in which the same is employed, the accompanying drawings disclose a collapsible box structure, which includes top, sides, and bottom of panels A, and end walls B.

The end walls may be constructed of double sections connected at their outer ends by cross bars C—C. As disclosed clearly in Figure

3, the end walls B have driven into their edge portions at spaced intervals novel members 1. These members have pointed shanks 2 provided with ribs or the like 3 for retaining the same within the end walls of the box when the same are driven thereinto. The head portion of each member is provided with a cylindrical portion 4, and a head portion 5, between which head portion and said cylindrical portion, a reduction 6 is formed. These members are driven into the edges of the end walls in the manner shown with the inner end of the cylindrical portions bearing against the edge of the walls in the manner as shown in Figure 3.

Certain headless nails 7 are also driven into the edges of the end walls and allowed to project a slight distance outwardly for a purpose hereinafter fully described.

The top, bottom, and side walls of the box are provided at their end portions with openings 8. These openings 8 are arranged in spaced relation, and when the walls A are arranged in proper relation to the end walls, the outer end portions of the members 1 are adapted to project through these openings 8, so that the said portion 5 and the reduced portion 6 thereof will extend beyond the outer sides of said walls.

Certain openings are also formed in the ends of the walls A to receive the projecting outer end portion of the nail 7, whereby the walls will be retained in position until the strap member hereinafter fully described, is secured in position.

The pair of end straps 9—9 are provided for each box, and each of these straps is constructed of a number of sections equal to the number of sides to the box. Driven into each of the end walls B is a driven member 10 of substantially the same construction as the members 1, excepting that the head portion 5 thereof projects a greater distance from the outer side of the side wall, when the latter is disclosed in position, than do the head portions of the other driven members.

Each section of the strap 9—9 is formed with a plurality of spaced key slots 11. These key slots are of usual formation, consisting of forming the strap with an opening 12, and

55

100

a reduced slot 13 extending for a short distance therefrom.

The end section of each strap is formed at its outer end with one of these key slots adapted for engagement over the driven elements 10. The several sections of each strap are linked together so that the same may be engaged around the corners of the box without buckling or distortion of the strap sections.

10 A substantially square link member 15 connects one side strap to a strip 16, said strip being provided with a pull ring 17 at its free end. The strip is provided with an opening 18 at an intermediate point. The opposite extreme side section of the strap is provided with an opening at its end portion for registry with the opening 18 when the strap is properly placed around the box. The remaining ends of the sections are connected by links 14. The head 5 of the member 10 is adapted to protrude beyond the registering openings, while the elongated reduced portion thereof accommodates the overlapping members.

15 By gripping the ring 17 and pulling the strap, that particular section of the strap will be secured in position by the engagement of the head portions 5 of the driven elements over the reduced slots 13 of the key slots.

20 In all the movements exerted in securing the straps to the driven elements, the ring 17 may be employed for exerting a pull on the strap. The straps may be constructed of spring metal, so as to prevent the sections from becoming bent, and to facilitate the engagement of the sections with the several driven elements.

25 40 If desired, an intermediate strap 19 may be secured about the intermediate portion of the box for preventing bulging of the side walls.

Having thus described the invention, what 45 I claim as new and desire to secure by Letters Patent is:—

1. In a collapsible box of the character described wherein the side walls of the box are formed with spaced openings adjacent their ends, stud members projecting from the edges of the end walls of the box and being adapted to project through said openings in the side walls, and a pair of straps formed with spaced key slots arranged around the ends of said box so as to engage the studs projecting through the side walls in secure relation with said straps through said key slots.

2. In a collapsible box securing means 60 wherein the side walls of the box are formed with spaced openings, stud members projecting from the edges of the end walls and being adapted to project through said openings in the side walls, and a pair of straps each constructed of a number of substantially

stiff sections equal to the number of sides to the box and being linked together, said linked connections being adapted to engage around the corners of the box, each section being formed with a plurality of spaced key slots adapted to engage the stud projecting through the side walls in secured relation with the said straps through said key slots.

3. In a collapsible box securing means 75 wherein the side walls of the box are formed with spaced openings adjacent their ends, driven members arranged around the edge of each end wall of the box, said members being provided with an enlarged head formed with an inwardly disposed reduced portion, said head and reduced portion of each member being adapted to project through the corresponding openings in the side walls of the box, and a pair of straps formed with spaced key slots arranged around the ends of said side walls of the box so that the studs projecting from the end walls of the box will engage in the key slots of the straps for securing the sides of the box to the end walls.

80 In testimony whereof I affix my signature.
HOMER H. VANDIVORT.
